UNITED STATES PATENT OFFICE

171,159

MEDICINE CABINET

Frank E. Knight, Saginaw, Mich.

Application September 26, 1952, Serial No. 21,602

Term of patent 14 years

(Cl. D4—3)

To all whom it may concern:

Be it known that I, Frank E. Knight, a citizen of the United States of America, residing at Saginaw, in the county of Saginaw and State of Michigan, have invented a new, original, and ornamental Design for a Medicine Cabinet, of which the following is a specification, reference being had to the accompanying drawing, forming part thereof.

In the drawing:

Fig. 1 is a perspective view of a medicine cabinet showing my new design.

Fig. 2 is a front elevational view thereof.

Fig. 3 is an edge elevational view.

I claim:

The ornamental design for a medicine cabinet, as shown.

FRANK E. KNIGHT.
